Co. LPA(57) **CLAIM**

An ornamental design for a male hose coupling, as shown and described.

DESCRIPTION

FIG. 1 is a front perspective view of a male hose coupling;
FIG. 2 is a side view of a male hose coupling;
FIG. 3 is a front view of a male hose coupling;
FIG. 4 is a rear view of a male hose coupling;
FIG. 5 is a rear perspective view of a male hose coupling;
FIG. 6 is a front perspective view of a male hose coupling of a second embodiment;
FIG. 7 is a side view of a male hose coupling shown in FIG. 6;
FIG. 8 is a front view of a male hose coupling shown in FIG. 6;
FIG. 9 is a rear view of a male hose coupling shown in FIG. 6; and,
FIG. 10 is a rear perspective view of a male hose coupling shown in FIG. 6.
